UNITED STATES PATENT OFFICE

DANIEL W. JANOVER, OF BROOKLYN, NEW YORK, ASSIGNOR TO S. GUMPERT CO. INC., OF BROOKLYN, NEW YORK, A CORPORATION OF NEW YORK

DESIGN FOR A CUP OR SIMILAR CONTAINER

Application filed April 25, 1932. Serial No. 43,605. Term of patent 3½ years.

To all whom it may concern:

Be it known that I, DANIEL W. JANOVER, a citizen of the United States, residing at 773 East 21st Street, borough of Brooklyn, county of Kings, State of New York, have invented a new, original, and ornamental Design for a Cup or Similar Container, reference being had to the accompanying drawing, forming part hereof.

The container consists of two portions, one portion being of metal to which the handles are fixed and the upper and inner portion being of a glass portion as shown.

I claim:

The ornamental design for a cup or similar container as shown and described.

DANIEL W. JANOVER.
